UNITED STATES PATENT OFFICE.

WILLIAM H. PAGE, OF NORWICH, CONNECTICUT, ASSIGNOR TO WILLIAM H. PAGE & CO., OF SAME PLACE.

DESIGN FOR PRINTING-TYPES.

Specification forming part of Design No. 7,249, dated March 17, 1874; application filed January 5, 1874.
[Term of Patent 7 years]

To all whom it may concern:

Be it known that I, WILLIAM H. PAGE, of Norwich, New London county, and State of Connecticut, have invented a Design for Poster-Border Printing-Types, of which the following is a specification:

The nature of my design is fully represented in the accompanying printed illustration, to which reference is made.

My design consists of similar pointed figures repeated through the whole length of the border, and arranged between two parallel stripes upon a dark ground, having a somewhat dif-

ferent figure to fill the corner spaces, similar, however, in its design to the side figures.

When white paper and black ink are used in printing this border, the figures and stripes will appear white upon a black ground.

I claim as my invention—

The design for a border, consisting of the figures between parallel stripes, upon a dark ground, substantially as shown and described.

WILLIAM H. PAGE.
